AUTOMATIC WASHING MACHINE HAVING A VARIABLE SPEED DRIVE

Erich Schmettow, Hohenbrunn-Riemerling, Germany, assignor to Siemens-Electrogerate Aktiengesellschaft, Berlin, Germany, a corporation of Germany
Filed Sept. 19, 1961, Ser. No. 139,584
Claims priority, application Germany Sept. 23, 1960
6 Claims. (Cl. 68—12)

My invention relates to drum-type washing machines, particularly to automatic electric washers, in which a laundry-receiving drum is driven from an electric motor for slow rotation of the drum during washing and rinsing and fast rotation during subsequent spin-drying.

Such different rotating speeds of the drum can be obtained and exclusively controlled with the aid of multi-stage mechanical speed-change transmissions, but such transmissions occupy much space and represent an expensive component if three or more transmission ratios are required. The expenditure in material and space increases considerably with the ratio of the required maximum (spinning) and minimum (washing) speeds. For good spin-drying, however, the spinning speed must be kept as high as feasible, whereas the washing speed for best laundering must have a much lower value, usually at about 50 r.p.m. Since furthermore the electric motors preferably employed for washing machines are of the squirrel-cage type, because they are not susceptible to trouble by sparking and require virtually no maintenance, and since such motors have a poor starting characteristic, namely a low torque at low speed and hence very low starting power, the design of a drive for drum-type washers employing such motors involves considerable difficulties which, as a rule, can be overcome only with heavy, large and expensive motors and/or with the aid of large and complicated transmission mechanisms. Another possibility of adjusting different driving speeds resides in the use of a pole-switchable squirrel-cage motor. However, in order to obtain the above-mentioned extreme change in transmission ratio between washing and spinning speeds, the necessary motors would have to have a very high pole-number ratio, for example 2:24 or more. Such motors are excessively heavy and expensive.

It is therefore an object of my invention, relating to automatic drum-type washing machines of the type described above, to devise a drive which permits using a relatively small electric motor in both stages of operation, namely for slow washing operation as well as for fast spin-drying, while securing an economical performance and obtaining a transition from washing to spinning with a highest feasible torque of the drive motor.

Another object of my invention is to devise a drive for such washing machines which, in the event the operating voltage should fail during the spinning operation, will automatically and without appreciable auxiliary devices, return into an operating condition in which the drive can readily commence with a new operating process. That is, the washing machine when operating in dry-spinning operation and then encountering voltage failure is supposed to return with particularly simple means and in a reliable manner into an operating condition which, as to drum speed, either corresponds to the washing stage or approaches it sufficiently to permit restarting the motor with a sufficient starting torque until the speed is automatically increased again up to the spinning value.

To achieve these objects and in accordance with a feature of my invention, I provide the drum-type washing machine between the electric drive motor and the laundry-receiving drum with a variable-speed transmis-

sion mechanism whose transmission ratio is continuously controllable from a lower to an upper limit value, in combination with a speed-responsive regulating means which preferably under direct or indirect control by the programming or other control device of the washing machine, automatically increase the drum speed up to the desired high spinning speed. The transmission mechanism thus automatically controlled then operates constrainedly to always maintain the drive motor at a favorable point of its torque characteristic while the speed of the drum is being built up to the spin-drying value.

Such a washing-machine drive can readily be so designed that it will automatically return to washing speed in the event the drive motor is subjected to voltage failure.

According to a more specific feature of my invention, the above-mentioned control and resetting operations are obtained by providing the ratio-regulating means of the transmission with a centrifugal device, such as a weight movable in dependence upon centrifugal force, for continuously varying the drum-speed. Such a centrifugally regulated transmission is automatically effective to increase the drum speed up to the desired maximum value at the beginning of a spin-drying operation and also sets the transmission mechanism back to low speed in the event of voltage failure.

According to a particularly simple embodiment of the invention, the electric drive motor of the washing machine always operates at a fixed speed and the speed change of the drum is effected exclusively by the change in transmission ratio within the transmission mechanism connecting the motor with the drum.

However, according to another, preferred feature of my invention, a considerable further improvement is achieved by providing for the input member of the regulatable transmission mechanism two selective speed steps, a lower speed to be effective during washing operation and a higher speed to be effective for spin-drying operation, the transmission mechanism having a fixed transmission ratio at the lower speed of its input member and commencing its ratio-changing operation only when the speed of the input member is switched to the higher value. This combination of the variable-ratio transmission with a two-step primary drive affords covering a particularly great range of speeds with relatively simple means.

According to a more specific feature of the type just mentioned, the change between the two steps of input speed for the variable-ratio transmission is effected by means of a two-stage speed-change gearing between a single-speed electric motor and the input member of the transmission mechanism. In such a machine, it is preferable to control the two-stage gear transmission by a control pulse supplied from the programming or control device of the washing machine, namely so that when this device switches the machine from washing to spinning, the gear transmission is simultaneously switched from low gear to high gear, the regulator of the continuously variable transmission mechanism being so set that it responds to the switching to increased primary driving speed, thus commencing the above-described automatic increase of the drum speed up to the desired spinning speed.

According to another, alternative feature of my invention, the change in input speed applied to the input member of the variable-ratio transmission mechanism is effected by providing the machine with a pole-switchable induction motor which in this case may have a relatively simple design because its pole number ratio need only be moderate, for example 2:4, as the further increase in drum speed is effected by the variable transmission between motor and drum.

According to a further feature of my invention, the

above-mentioned variable-ratio transmission comprises an endless V-belt with belt sheaves of adjustable effective diameter, belt transmission of this type being generally known as such. The diameter-changing control of one or both belt sheaves can then be effected directly by the centrifugal regulator cooperating with a counter spring. When providing two adjustable belt sheaves, it is preferable to mount the spring, to oppose the centrifugal force, upon the displaceable portion of one of the sheaves and to mount the centrifugal weights upon the displaceable portion of the other sheave. In this manner, the spring and the pre-tension produced thereby have the effect of determining the rotating speed at which the centrifugal regulator will commence operating, and the same spring then simultaneously serves to maintain substantially uniform tension in the belt.

Such a V-belt transmission in a washing machine according to the invention may also be of the two-stage type. In this case, an intermediate shaft is provided between the motor shaft and the drum shaft. The intermediate shaft is preferably provided with two belt-sheave portions which are fixed in the axial direction relative to each other, and also with two belt-sheave portions which are displaceable axially in the same sense so that the displacement increases the effective sheave diameter for one of the two belts and simultaneously reduces the effective sheave diameter for the other belt. In a transmission of this type, the axial pressure upon the V-belts in the two transmission stages would be approximately equal, disregarding the differences in the groove angle which in any event remain within very narrow limits. However, since the torques in such a plural-stage transmission and hence the pulling forces transmitted by the respective belts, differ greatly from each other in accordance with the step-down or step-up ratio, the faster running belt would be subjected to a considerably higher pressure force than the other belt because the force of the counter spring must adapt itself to the slowly running stage where higher torques are effective. In the fast-running stage, the high pressure in conjunction with the high belt speed may result in excessive heating and great wear of the belt.

According to a more specific feature of my invention, however, these difficulties are obviated as follows. A compensating spring is mounted on the intermediate shaft between an axially fixed belt portion and the axially movable belt portions, and the force of the compensating spring is directed against the action of the counter spring mounted on the drum shaft, thus reducing the axial stress imposed upon the belt in the fast running transmission stage. With the counter spring on the drum shaft and the compensating spring on the intermediate shaft thus acting in opposition to each other, the centrifugal regulating device correlated to the motor shaft need overcome only the difference of the two spring forces. This is favorable to the performance of the transmission mechanism because this difference is relatively small if the centrifugal weights, when in starting position, are located in the vicinity of the motor-shaft axis where the centrifugal force is initially slight because of the small radius. During the regulating operation the radius increases, the centrifugal force also increases, and the difference between the two spring forces to be overcome by the centrifugal force also increases. Consequently, an adaptation of centrifugal force and spring forces is readily possible.

The above-mentioned and other objects, advantages and features of my invention, said features being set forth with particularity in the claims annexed hereto, will be apparent from, and will be described in, the following with reference to the embodiments of drum-type washing machines according to my invention illustrated by way of example on the accompanying drawings in which:

FIG. 1 shows schematically the components of a drum-type washing machine essential to the invention including the laundry-receiving drum, the variable-ratio trans-

mission, a pole-switchable, drive motor and a program-control device.

FIG. 2 shows schematically in a substantially similar manner a washing machine with a single-speed motor and a two-stage speed-change gear interposed between the motor and the variable-ratio transmission.

FIG. 3 shows schematically a side view of part of FIG. 1 or 2.

FIG. 4 shows a side view similar to FIG. 3 but relating to a somewhat modified design.

FIGS. 5a and 5b illustrate in section the upper and lower belt sheaves respectively of the variable-ratio transmission according to FIGS. 1 to 4, each illustration showing two different operating positions.

FIG. 6 is a speed-time diagram explanatory of the performance of machines according to the invention.

FIG. 7 shows in section a two-stage belt transmission of variable ratio applicable in washing machines otherwise corresponding to those of the preceding embodiments; and

FIG. 8 is an explanatory diagram relating to the performance of the transmission according to FIG. 7.

As shown in FIG. 1, the drum 1 of a washing machine is driven from a pole-switchable squirrel-cage motor 2 capable of selectively operating at two speeds depending upon which group of poles is energized at a time. Such motors are commercially available as standard products. They may have two and four poles, for example, to operate at a speed ratio of 2:1. Driving power is transmitted from the shaft 11 of the motor 2 to the shaft 19 of the drum by a variable-ratio mechanism consisting of a V-belt drive which comprises a two-part belt sheave 3 on the drum shaft 19, a two-part belt sheave 4 on the motor shaft 11, and an endless V-belt 8. The motor 2 is energized from power-supply terminals 20 under control by a programming control device 7 illustrated as a drum-type contactor in planar developed form, which is provided with contact segments 5 and fixed contacts 6. The control device 7 is essentially an electrically driven timer as customary for automatic washing machines. When the control device 7 is in Low position, one group of poles in motor 2 is active for operation of low speed and the drum 1 is driven for washing operation. When the device 7 advances to High position, the other group of poles in motor 2 is energized for driving the drum 1 at higher speed. As explained, the transmission 3, 4, 8 now becomes effective to change its transmission ratio so as to gradually increase the drum speed above the value that it would assume if the drum were simply driven at the speed of motor 2. Such increase continues until the drum 1 has reached the desired high spin-drying speed. Details of the variable-ratio transmission and its operation will be described in a later place.

The embodiment schematically illustrated in FIG. 2 is to some extent similar to that of FIG. 1, identical components being denoted by the same reference numerals respectively. According to FIG. 2, a single-speed two-pole drive motor 22 is used. It drives a two-staged mechanical gear transmission 24 which in turn drives the input sheave 4 of the above-mentioned variable-ratio transmission. The two speed steps of gear transmission 24 are electromagnetically controlled by respective control windings 26 and 28 so that only the one gear step is active whose appertaining control winding is energized at a time. The program control device 27, when turning from Stop to Low position, energizes by means of its contact segments 25, the motor 22 and simultaneously the control winding 26 so that the drum 1 is driven for washing operation at slow speed. When thereafter the control device 27 switches to High position, the motor 22 remains energized but now the control winding 28 is energized so that the input sheave 4 of the variable-ratio transmission operates at higher speed

and the variable-ratio transmission commences to increase the drum speed up to the spinning value.

As will be more fully apparent from FIGS. 5a and 5b, each belt sheave 3 and 4 in FIGS. 1 and 2 comprises a half-portion fixed to the shaft on which the sheave is mounted, whereas the other half portion is axially displaceable so that the V-groove of the sheave can become wider or narrower. This should be kept in mind with reference to the lateral view illustrated in FIG. 3, showing the two extreme positions of the endless belt 8. Shown by a full line is the operating condition of the belt for the low drum speed. Shown by a broken line is the operating condition for the high drum speed.

FIG. 4 illustrates a modified embodiment in which the belt sheave 3' on the shaft 19 or drum 1 has a fixed effective diameter (i.e. does not consist of two portions of which one is axially displaceable relative to the other) and only the belt sheave 4 on the motor shaft 11 can vary its effective diameter for changing the transmission ratio. In this case, a tensioning roller 9 is provided for compensating the different belt lengths during changes in transmission ratio. The roller 9 is pressed against the belt 8 in the direction of the arrow, for example by means of a spring, and may be journaled, for example, on an arm (not shown) pivotally mounted on the motor shaft 11. During operation at low drum speed, the tensioning roller 9 is in the full-line position at the left, and the V-belt 8 runs with the smallest diameter of the driving sheave 4 on the motor shaft 11. At the highest drum speed, the roller 9 occupies the broken-line position, and the driving sheave 4 is active with its largest diameter.

As more fully shown in FIGS. 5a and 5b, the driving belt sheave 4 in a machine according to FIGS. 1 or 2 comprises a disc 12 rigidly joined with the shaft 11 of the electric motor 2, and a disc 13 axially displaceable on the shaft 11. A helical pressure spring 14 tends to force the disc 13 away from disc 12 to the limit position shown in the upper portion of FIG. 5b. In this position, the driving belt is in its innermost operating position 8a so that a relatively small driving-sheave diameter is effective. This position corresponds to the washing operation of the drum. When passing to the spin-drying operation, initiated by switching of the motor 2 (FIG. 1) to high speed, the revolving speed of the motor shaft 11 increases. When it reaches a given value, a centrifugal weight 15, pivotally connected at 16 with the driving disc 12 by a sleeve 17, is lifted and then forces a pressure dog 18 against the displaceable disc 13. As a result, the disc 13 is gradually forced toward the disc 12 in opposition to the force of spring 14 to the limit position shown in the lower portion of FIG. 5b. In the latter position, the driving belt is in the position 8b in which the largest diameter of the driving sheave is effective.

The driven sheave 3 (FIG. 5a) comprises a disc 20 rigidly joined with the shaft 19 of the washer drum 1, and a disc 21 axially displaceable relative to disc 20. A helical compression spring 22 forces the disc 21 toward the disc 20, so that the disc 21 assumes the broken-line position during washing operation and the driving belt occupies the position 8a corresponding to the largest effective diameter of the driven sheave 3. During spinning-drying operation, the belt is forced downward to the position 8b so that the disc 21 occupies the full-line position in which a smaller diameter of the driven sheave 3 is effective. This is due to the action of the centrifugal weight 15. If desired, however, the upper sheave 3 may also be provided with a centrifugal device corresponding to that shown in FIG. 5b and set to operate simultaneously with, and in the same manner as, the device described above with reference to FIG. 5b.

The coordinate diagram of FIG. 6 is typical of the performance obtained with a washing machine according

to the invention. The abscissa denotes time (*t*), and the ordinate indicates the rotating speed (*n*) of the drum in revolutions per minute. Upon to the moment *t*₁, the machine runs in washing operation. At this moment, the two-stage drive is switched from Low to High by the program control device of the machine (7 in FIG. 1, 27 in FIG. 2). Now the drum speed *n* increases up to the moment *t*₂ in which the centrifugal regulator (15) becomes active. The moment *t*₂ is reached when balance obtains between the centrifugal force of the regulator and the force of the counter spring. These two forces must be given such an approximate dimensioning that *t*₂ would be attained at about a drum speed of 60 to 70% of the speed effective if only the high switching stage of the gear transmission 24 (FIG. 2) or of the pole-switchable motor 2 (FIG. 1) were permitted to operate and the variable-ratio transmission were kept at a fixed ratio. At the just-mentioned speed the maximum power of the motor is substantially reached. Beginning with the moment *t*₂, the regulator 15 causes the speed of drum 1 to be increased by the continuously regulatable transmission up to the maximum value which is reached at the moment *t*₃. That is, from moment *t*₂ to moment *t*₃ the drum speed is being increased from the low washing speed up to the spinning speed, and the spin-drying operation proper commences with the moment *t*₃.

A two-stage variable-ratio transmission embodying the above-mentioned features of the invention will be described presently with reference to FIG. 7 and with reference to the diagram of FIG. 8 indicating the forces acting upon the counter spring and compensating spring in dependence upon the amount Δx displacement.

The transmission mechanism shown in FIG. 7 is applicable in lieu of the single-stage variable-ratio transmission of the embodiments described above, in conjunction with an electric drive motor and a control device as shown in FIG. 1, or in conjunction with a motor, two-step gear transmission and control device as shown in FIG. 2. It may be assumed, for example, that the input sheave of the variable-ratio mechanism according to FIG. 7 is driven from a pole-switchable motor with two and four selectively operable poles. Denoted by 31 in FIG. 7 is the shaft of the washer drum, by 32 the shaft of the motor, and by 33 the above-mentioned intermediate shaft.

The driving sheave on the motor shaft 32 comprises an axially fixed portion 34 and an axially displaceable portion 35 which jointly cooperate with a V-belt 36. Mounted on the motor shaft and axially rigid relative thereto is a guiding body 37 for centrifugal weights 38. When the motor shaft rotates at a speed above a given value, the weights 38 move outwardly in the directions indicated by arrows 39 and press the axially displaceable portion of the belt sheave toward the left in the direction of the arrow 40 thus providing for the increased driving speed of the drum required for spin-drying operation.

The intermediate shaft 33 carries two axially fixed belt-sheave discs 41 and 42 between which an axially displaceable middle structure is mounted which forms two sheave portions 43 and 44. The belt sheave 36 engages the sheave portions 43 and 44. Another belt 45 engages the sheave portions 41 and 43 and serves for driving the belt sheave on the drum shaft 31.

The drum shaft 31 carries an axially fixed sheave disc 46 and an axially displaceable disc 47, both cooperating with the V-belt 45. A helical counter spring 48 mounted on the drum shaft 31 tends to force the displaceable disc 47 toward the fixed disc 46. A helical compensating spring 49 is mounted on the intermediate shaft 33 between the axially fixed portion 42 and the axially displaceable middle structure 43, 44. Spring 49 acts in opposition to the force of the counter spring 48.

In FIG. 7, the belt position corresponding to the washing operation is shown by full lines, whereas the belt posi-

tion corresponding to the spin-drying operation is indicated by broken lines.

In the graph shown in FIG. 8, the horizontal reference line indicates the direction of displacement caused by the centrifugal motion of the weights 38, this motion being in the direction of the arrow 40 and causing a compression of the counter spring 48 and of the compensating spring 49. The amount of displacement thus centrifugally effected extends from a_1 to a_2 . Plotted on the displacement line are the spring forces of the counter spring 48 (G_1, G_2) and the spring forces of the compensating spring 49 (A_1, A_2), so that the force difference F_1 or F_2 to be overcome by the centrifugal force of the weights 38 is apparent. The increase of the difference valve from F_2 to F_1 can be dimensioned by corresponding choice of the springs 48 and 49 so that it corresponds to the increase in centrifugal force acting upon the weight 38 during automatic regulating operation.

When employing such a two-stage belt mechanism, the increase in force of the counter spring on the drum axis can be kept very small, in some cases even negative, corresponding to the torques to be transmitted on the drum shaft. With the corresponding increase in force of the compensating spring on the intermediate shaft, the increase in the difference between the two spring forces can be so dimensioned that it corresponds to the increase of the centrifugal force acting upon the centrifugal regulator so that a favorable regulating characteristic is obtained.

Upon study of this disclosure, it will be obvious to those skilled in the art that my invention is amendable to a variety of modifications and hence can be given embodiments other than particularly illustrated and described herein, without departing from the essential features of the invention and within the scope of the claims annexed hereto.

I claim:

1. In a drum-type washing machine having a laundry-receiving rotatable drum, drive means for said drum, and a program control device connected with said drive means for sequentially switching it to operate at a lower speed range for washing operation and at higher speed range for centrifuging operation, said drive means including a motor and a two-step gear transmission mechanism disposed between said motor and said drum and shiftable between a first and second speed for transmitting power to said drum and increasing the speed thereof, a continuously variable V-belt transmission having a pair of sheaves each having a displaceable disc and connected between said two-step transmission mechanism and said drum for controlling acceleration of said drum within said higher speed range, and a centrifugal weight device joined with a first one of said sheaves and engaging the displaceable disc of said first sheave for displacing the latter in dependence upon the second speed of said two step transmission, said control device having means for sending a signal pulse to shift said transmission from a said first speed to said second speed, said centrifugal device being responsive to the two-step transmission reaching said second speed.

2. In a washing machine according to claim 1, said motor having a single operating speed.

3. In a washing machine according to claim 1, said V-belt transmission having a variable transmission ratio, said first sheave being of variable effective diameter and coaxially joined with said drive means; a counter spring engaging said first sheave and biasing it in the direction required to reduce said transmission ratio, said centrifugal weight device being movable outwardly by centrifugal force and operatively connected with said first sheave for varying said diameter in opposition to said spring to increase said transmission ratio.

4. A washing machine according to claim 1, including a counter spring in engagement with said displaceable disc of said first one of said sheaves for biasing it away from said fixed disc of said one sheave, and said weight means having a pivot axis in fixed relation to said axially fixed disc of said one sheave and being centrifugally movable outwardly about said axis for displacing said displaceable disc of said one sheave in opposition to force transmitted by said belt from said spring.
5. In a drum-type washing machine having a laundry-receiving rotatable drum, drive means for said drum, and a control device connected with said drive means for sequentially switching it to operate at low speed for washing operation and high speed for spin-drying operation, the combination of a transmission mechanism disposed between said drive means and said drum and having a transmission ratio continuously variable between a lower and an upper limit, said mechanism having control means responsive to operation of said control device for causing said ratio to continuously vary in the drum-speed increasing sense up to the spin-dry speed when said drive means is switched from washing to spin-drying operation, said transmission mechanism comprising a two-stage V-belt transmission having a first sheave coaxially joined with said drive means, a second sheave coaxially joined with said drum, an intermediate shaft parallel to the axis of said two sheaves, a twin sheave on said shaft, and two endless belts drivingly connecting said first sheave with said twin sheave and connecting said twin sheave with said second sheave respectively; each of said first and second sheaves having two component discs of which one is axially fixed and the other is axially displaceable, said two discs forming together a belt-engaging groove whose effective diameter varies with the displacement of said other disc; a centrifugal weight device joined with said first sheave and engaging the displaceable disc of said first sheave for displacing it in dependence upon the speed of said drive means; a counter spring engaging said displaceable disc of said second sheave and having a force direction opposed to the action of said centrifugal weight device; said twin sheave comprising two axially fixed discs and two intermediate disc members jointly displaceable axially in the same sense so as to form together with said two latter fixed discs two belt-engaged grooves which inversely vary their respective diameters with axial displacement of said disc members; and a compensating spring mounted on said intermediate shaft and in biasing engagement with said disc member in a force direction opposed to the effect of said counter spring, whereby said compensating spring reduces the axial stress imposed upon the belt running at greater speed than the other.
- 40
- 45
- 50
- 55
- 60

6. In a washing machine according to claim 5, said counter spring and said compensating spring having respective spring characteristics adapted to each other so that the difference of their respective forces increases substantially in accordance with the increase in centrifugal force of said centrifugal device during the ratio-changing operation of the transmission mechanism.
